A new and improved hand loom and method of weaving
with the aid of a warp rod to provide a loom, the
same being of simple and compact design, which
is particularly adapted for use in weaving
small pieces of material, and which is
designed to be easily and quickly assembled
and disassembled, and which is particularly
adapted for use in weaving small pieces of
material, and which is designed to be easily
and quickly assembled and disassembled.

HAND LOOM

Josephine M. Ryan, Vancouver, British Columbia,
Canada

Application June 19, 1939, Serial No. 279,869

4 Claims. (Cl. 139—34)

5 My invention relates to improvements in hand
looms the objects of which are to provide means
whereby a piece of material of substantial length
may be woven on a device of considerably less
length than that of the material; to provide
means whereby the warp may be applied, if de-
sired, as a continuous strand so that only the
starting and finishing ends need to be knotted.
Further objects are to provide means whereby
10 the loom may be adjusted to suit the length and
breadth of material to be woven, and also to pro-
vide means for maintaining the selvedges of the
material parallel throughout the length of the
piece.

15 The invention consists of a pair of end frames
between which spaced rods are supported for the
purpose of carrying the warp, as will be more
fully described in the following specification and
shown in the accompanying drawing, in which:

20 Fig. 1 is a perspective view of the invention
showing the warp in place.

Fig. 2 is a perspective view showing two looms
coupled together to increase the warp length.

25 Fig. 3 is a detailed sectional view showing the
connection of the warp rods to the end frames.

Fig. 4 is a fractional perspective view of a modi-
fication showing adjustable frames.

Fig. 5 is a fractionated view of one of the rod
holders.

30 In the drawing like characters of reference in-
dicate corresponding parts in each figure.

The numeral 1, see Figures 1, 2 and 3, indicates
a pair of end frames each having a central open-
ing 2. The edges of each end frame may be
35 transversely slotted as at 3 to guide the user in
spacing the rows of weft when weaving.

40 The end frames 1 are spaced apart as shown
and support warp rods generally indicated by the
numeral 4, each of which has a threaded socket
5 at one end and a screw projection 6 at the
other and may be made up of two or more
lengths 7 as shown in Figure 3. The warp rods
are secured to the end frames by thumb screws
45 8 and thumb nuts 9 respectively. Mounted upon
each warp rod 4 is a pair of rings 10, each of
which include a transversely disposed eye 11 for
the purpose of receiving one end of a weft sel-
vedge pin 12, see Figure 1. In Figure 2, two end
50 frames 1 are lapped together as at 14 at each
end of the loom so that six warp rods are used
in place of four, and the total warp length around
the loom is materially increased over that shown
in Figure 1.

55 It will be noted that with these looms the warp

threads are tightly wound around the loom first
and the weft is subsequently interwoven.

In the modification shown in Figures 4 and 5,
the end frames are generally indicated by the
numeral 18, and each consists of a pair of plates
19 having slots 20 adjacent their outer edges.
Each plate 19 is provided with a diagonally ar-
ranged groove or channel 21 in which a pair of
spreader 22 are adjustably secured. The plates
19 are adapted to be clamped together by thumb
10 nuts 23 to hold the spreaders in adjusted position.

Each spreader 22 consists of a rod 24 having a
head 25, the head being provided with one or
two recesses 26 formed in its outer end. Each
of the recesses is of the same width as a warp
rod 27 and where two recesses are formed in each
head the dividing wall 28 between said recesses
projects beyond the main portion of the head,
so as to lie flush with the outer edge of the warp
rod 27, as shown in Figure 5. The ends of each
warp rod 27 are turned downwardly at a right
angle as at 29 and their terminal ends are bent
back substantially upon themselves to form spring
loops 30 which may be frictionally held within
25 their respective recesses.

Where it is desired to extend the length of the
structure as shown in Figures 4 and 5, it suffices
to add other lengths of warp rod 27 to one end
frame and add another end frame at the outer
30 end of the added rods.

In operating the device as shown in Figures 1,
2 and 3, the warp indicated by the numeral 31,
is wound around the loom in a single layer as
shown in Figure 1, the ends of the warp being
tied either to the weft rods or to the end frames
1. The weft, indicated by the numeral 32, is
suitably secured at one end of the frame and is
passed to and fro across and between the warp
threads to weave any desired pattern. In order
40 that the tension on the weft may be prevented
from drawing the warp threads too closely to-
gether, especially between adjacent warp rods 4,
selvedge pins 12 are placed through comple-
mentary eyes 11 of rings 10 and are brought close
45 to the outer warp threads. The weft threads
are passed around the pins 12 and are then
passed again through the warp, by so doing the
selvedges 33 are kept straight without difficulty.
As soon as one side panel has been woven, the
pins 12 are withdrawn from the selvedge and are
placed in the new position on the next side panel
50 to be woven. When the work is completed, one
end frame 1 is detached from its warp rods and
the material, now in tubular form, is removed
55

and cut transversely to produce the finished length of woven material.

The weft is interlaced through the warp either by a needle, a knitting needle or other suitable device.

Should it be desired to make the material with finished edges all around, the warp could be applied by passing it around the loom in alternate directions, see Figure 2, where it is shown as starting at the warp rod 4X, passing first in an anti-clockwise direction around the loom, again to the rod 4X, thence passing in a clockwise direction to the rod 4X again and so on. To illustrate this, the warp strands are shown well separated.

When the warp is applied to the loom in this manner, the material woven, when removed from the loom, will be found to be a rectangular piece having the warp edges finished in the same manner as selvedges.

If desired to weave a piece of material considerably longer than the loom one selvedge only is provided and the free ends of all the weft threads extend to one end frame to which they may be secured until the length of material upon the loom is completed. When this is done, a portion of the finished material is removed, new warp is wound around the loom and the free ends of the weft threads are interlaced through the newly applied warp.

In the modification shown in Figures 4 and 5, the spreaders 22 are adjusted radially until the warp rods 27 are suitably spaced to give the wanted warp length, the thumb nuts 23 are then tightened to clamp the spreaders in adjusted position. The use of the device is the same as

above described, but due to the fact that there is no projection radially of the warp rods, the finished weave may be removed without dismantling the loom in any way.

What I claim as my invention is:

1. A hand loom comprising a pair of polygonal end frames spaced apart, a plurality of warp rods spaced apart and supported adjacent the angles of said end frames, said warp rods extending from one end frame to the other, one end frame being removably secured to the warp rods and a pair of spaced pins mounted to extend across two adjacent warp rods, said pins being detachably connected to the warp rods.

2. A hand loom comprising a pair of polygonal end frames spaced apart, a warp rod extending from each angle of one end frame to the corresponding angle of the second end frame, said rods being so spaced that the application of warp around the rods will form as many distinct areas of warp threads as there are angles to the end frames, one of said end frames being removably secured to the warp rods.

3. A hand loom comprising a pair of polygonal end frames spaced apart, warp rods extending at right angles from the plane of each frame, one of said warp rods connected to each angle of said end frames, the connection between the warp rods and one end frame being detachable.

4. A hand loom as claimed in claim 3, said end frames having a central opening and the peripheral edges of said end frames being transversely slotted to form spacing guides for the weft threads.

JOSEPHINE M. RYAN.
